UNITED STATES PATENT OFFICE.

HARRY B. HILLS, OF TOMPKINSVILLE, NEW YORK, ASSIGNOR TO STEWARD DAVIT & EQUIPMENT CORPORATION, OF NEW YORK, N. Y., A CORPORATION OF NEW YORK.

LINE-CARRYING GUN.

1,332,338.

Specification of Letters Patent. Patented Mar. 2, 1920.

Application filed July 18, 1919. Serial No. 311,745.

To all whom it may concern:

Be it known that I, HARRY B. HILLS, a citizen of the United States, residing at Tompkinsville, county of Richmond, and 5 State of New York, have invented certain new and useful Improvements in Line-Carrying Guns, of which the following is a specification.

My invention relates to line carrying guns. 10 It has for its object not only to simplify the operation of guns of this type, but the making of a compact structure that can be easily stowed and has a low center of gravity so that jumping due to recoil is reduced to a 15 minimum.

I will describe a line carrying gun embodying my invention and then point out the novel features thereof in claim.

In the accompanying drawing, Figure 1 20 is a side elevation of a line carrying gun and embodying my invention. Fig. 2 is an end elevation of the gun illustrated in Fig. 1. Fig. 3 is a sectional view taken on the line 3—3 of Fig. 1.

25 Similar letters of reference designate corresponding parts in all of the figures.

A designates a carriage which as shown comprises a base a and uprights a^1 , a^2 , preferably in a unitary design and of cast steel.

30 Preferably the uprights are so arranged on the base as to provide for the extensions a^3 and thereby secure greater stability for the entire device when it is fired. Each upright is provided with a journal a^4 and a plurality 35 of openings a^5 arranged in an arc. Each upright is also provided with an eye a^6 by means of which the carriage can be lashed in place.

B designates a gun having the usual bore 40 b to receive the firing charge and projectile to which a line is attached. b^1 , b^1 designate trunnions which are supported in the journal a^4 . The trunnions are provided at the 45 end of the gun and when the gun is mounted in the carriage it will be observed that it is

quite close to the base, thereby keeping the center of gravity of the gun low and close to the base as well as the force of recoil. The gun is also provided with a band b^2 , here shown as being split and fitting in a groove 50 b^3 and held in said groove by a bolt b^4 . The band is also provided with an opening through which a pin C passes. By reason of the fact that the band is split, each end thereof is provided with an opening b^5 , the 55 two openings constituting the opening aforesaid. The elevation of the gun is secured by means of the pin C, which is passed through a pair of opposite openings a^5 in the uprights and the openings b^5 in the ends 60 of the band.

When the device is not in use the gun is lowered between the uprights and secured in this position by the pin C which is passed through the lowermost openings a^5 and the 65 openings b^5 . Thus a compact arrangement is secured so that the gun can be easily stowed away.

Having thus described my invention, what I desire to claim as new is—

70 In a line carrying gun, in combination, a carriage comprising uprights in each of which are a plurality of openings arranged in an arc, and each provided with a base; a journal in each upright close to its base; a 75 gun; trunnions on the gun at one end thereof and carried in said journals; a band carried by said gun and provided with an opening; and means for holding the gun in various positions relatively to said base comprising a pin which is passed through a pair 80 of openings in the uprights and the opening in the band.

85 In witness whereof, I have signed my name to this specification, in the presence of two subscribed witnesses.

HARRY B. HILLS.
